(57) **CLAIM**

The ornamental design for a bicycle frame, as shown and described.

DESCRIPTION

1. Bicycle frame

1.1 is a bottom and right side perspective view of a bicycle frame embodying my new design;

1.2 is a top plan view thereof;

1.3 is a bottom plan view thereof;

1.4 is a front elevation view thereof;

1.5 is a rear elevation view thereof;

1.6 is a right side view thereof;

1.7 is a left side elevation view thereof;

1.8 is a perspective view thereof; and

1.9 is a bottom and left side perspective view thereof.

The broken lines in the drawings illustrate portions of the bicycle frame that form no part of the claimed design.

1 Claim, 9 Drawing Sheets
